UNITED STATES PATENT OFFICE.

KNUD KNUDSEN, OF PLAINVILLE, CONNECTICUT, ASSIGNOR TO THE TRUMBULL ELECTRIC MANUFACTURING COMPANY, OF PLAINVILLE, CONNECTICUT, A CORPORATION OF CONNECTICUT.

ELECTRIC SWITCH.

1,370,501.

Specification of Letters Patent.

Patented Mar. 1, 1921.

Application filed November 11, 1918. Serial No. 262,037.

To all whom it may concern:

Be it known that I, KNUD KNUDSEN, a subject of the King of Denmark, (signified intention of becoming a citizen of the United States and taken out first papers and applied for second,) residing at Plainville, Connecticut, have invented a new and useful Electric Switch, of which the following is a specification.

10 The present invention relates to electric switches and the objects of the invention are to provide simple and practical means for stopping and releasably holding the switch in a predetermined position—usually the circuit-open or “off” position.

Briefly stated the invention resides in the combination with the movable switch element and the operating means therefor, of a set of coöperating reversely inclined stops 20 arranged to engage in the movement of the switch and to interlock in such a way as to stop and frictionally hold the switch in a predetermined position.

The various features of the invention and 25 details of construction, etc., will all appear as the specification proceeds and will be more fully understood from consideration of the accompanying drawing which illustrates the invention as embodied in a concrete, 30 practical form.

In said drawing:—

Figure 1, is a front elevation of an inclosed or “safety” switch embodying the features of the invention, certain parts being 35 shown as broken away for the sake of greater clearness.

Fig. 2, is a broken side elevation of the same. In these first two views, the switch is shown in the closed position and in Fig. 2 40 the open circuit position of the parts is indicated in dotted lines.

Figs. 3 and 4 are detail views showing the complementary faces of the two interlocking members.

Fig. 5, is a broken side view of the handle member.

Fig. 6 is a detail sectional view, showing the inclined cams or stop shoulders.

The switch illustrated is of the knife blade 50 type embodying pivoted switch blades adapted for engagement with the relatively stationary contacts 6 and operated by an arm 7 connected to and forming a part of the switch operating member or handle 8.

This handle is pivotally supported by having a hub portion 9 journaled in the side wall of the box or casing 10 which incloses the switch parts, the arm 7 being shown as directly engaged with this hub portion 55 within the box.

The stop mechanism is carried by the two coöperating disk members 11 and 12 carried by the handle and the adjacent side wall of the box respectively. On the inside face of the disk 11 on the handle are provided a 60 pair of outstanding inclined cams or stop shoulders 13, disposed at opposite sides of the center of pivotal support of the handle and arranged to coöperate with these inclined cams are a pair of relatively stationary reversely inclined cams 14 on the opposing face of the relatively stationary disk member 12. 65

In the switch illustrated, the coöperating stop cams are so disposed that in the closed 70 position of the switch they will be entirely free of each other and so that they will become engaged and interlock as the switch is fully opened. The switch is thrown to its open position in the present disclosure by 75 means of a spring 15 connected with the operating arm 7 at one end and anchored to a relatively stationary support 16 at its opposite end. This spring serves to open the switch with a quick movement and the engagement of the coöperating inclined cams 80 brings the switch parts to rest without too sudden a jar and holds the switch parts in such open position, preventing any rebound or movement in a switch closing direction. 85 The switch parts will remain in this open position until sufficient force is exerted on the handle to overcome the friction of the inclined cams. This prevents accidental movement of the switch in a closing direction which otherwise might occur from excessive vibrations or the like. 90

The switch is usually provided with a latch such as that indicated at 17 for securing it in the closed position. With such a 10 construction the spring 15 is made of sufficient tension to snap the switch quickly open when this latch is released. With this construction therefore, the switch is positively held in the closed circuit condition 10 and furthermore when opened is firmly held in that position. Improper or accidental operation of the switch is therefore positively 105

guarded against. The latch for holding the switch closed may be controlled by a no-voltage or low-voltage release magnet, such as indicated at 18.

5. I claim:—

1. In an electric switch, the combination of a movable switch element, an operating handle therefor, a disk member carried by said handle, a relatively stationary disk member opposed to said disk on the handle and coöperating reversely inclined stop cams on the opposed faces of said disk members.
2. In an electric switch, the combination of a box, an annular member carried by the side of the box having a laterally extending cam face, and a switch operating handle having a hub journaled in said annular member and having a cam face adapted to coöperate with the said annular member to frictionally retard the opening movement of the switch and hold the parts in the open circuit position.
3. In an inclosed switch, the combination of a box, a movable switch element in the box, an external operating handle having a hub extending through the side of the box and an inclined cam face, and a reversely inclined cam member carried by the side of the box around said hub, said inclined cam members being adapted to co-act to frictionally check the opening movement of the switch.
4. In an inclosed switch, an annular bearing member having a plurality of inclined cam faces, and an operating handle member

having a hub portion journaled in said bearing member and having reversely inclined cam faces co-acting with the cam faces of said bearing member for the purpose described.

5. In an inclosed switch, a switch member movable therein, a bearing member secured to the side of the box, and an external operating handle journaled in said bearing member and connected to operate said switch member, said handle and said bearing member having coöperating reversely inclined stop shoulders.

6. In an electric switch, the combination of a pivoted movable switch element, an operating handle therefor, an inclined stop cam carried by the operating handle, and a relatively stationary reversely inclined stop cam opposed to the stop cam carried by the operating handle and coöperating therewith to stop the switch in one position.

7. In an inclosed switch, a base having stationary and pivoted switch members mounted thereon, a box inclosing said base and switch members, an operating handle mounted in said box and having connection with said movable switch member, and means for frictionally stopping the opening movement of the operating handle, said means consisting of an inclined projection carried by the box and a reversely inclined projection carried by the operating handle to engage the projection carried by the box when the switch is thrown to open position.

KNUD KNUDSEN.
